FIFTH WHEEL

Frank H. Kayler, Alliance, Ohio, assignor to
American Steel Foundries, Chicago, Ill., a cor-
poration of New Jersey

Application July 16, 1949, Serial No. 105,080

2 Claims. (Cl. 280—33.05)

1

This invention relates to a fifth wheel incorporating a coupling mechanism of the type shown and described in Patent No. 2,015,313, issued in the United States Patent Office on September 24, 1935, to Edmund P. Kinne, and more particularly to an improvement in the locking means for said mechanism.

A general object of the invention is to provide lock means for such a coupler which will have a rapid positive locking action and which, when in locking position with the coupler, is positively prevented from moving to unlocking position such as will accommodate uncoupling of the coupler.

The invention contemplates the provision of actuating means in the form of springs for the locking means arranged in an efficient manner to urge the lock into locking engagement with the coupler when the latter is in coupling position.

A further object of the invention is the provision of locking means which may be incorporated in couplers of the type described and presently in use.

These and other objects of the invention will become more apparent from the specification and the drawings, wherein:

Figure 1 is a perspective view of a fifth wheel assembly incorporating the invention, the fifth wheel being shown in phantom lines to more clearly illustrate the coupling and locking mechanism;

Figures 2 to 4 are vertical sectional views taken substantially on the line A—A of Figure 1, Figure 2 illustrating the mechanism in locked or coupling position, Figure 3 showing the mechanism in lockset position for uncoupling, and Figure 4 showing the mechanism in uncoupled position;

Figure 5 is a vertical sectional view taken substantially on the line B—B of Figure 1 with the mechanism in lockset or uncoupling position as in Figure 3; and

Figure 6 is a top plan view of the locking member.

Figures 7 to 9 illustrate a modification of the invention for use with heavy duty fifth wheels, Figures 7 and 8 being views comparable to Figures 2 and 5, respectively, and Figure 9 being a top plan view of the modified form of locking member.

Describing the invention in detail, the fifth wheel, generally designated 2, comprises a top plate 4 forked towards its rear extremity to provide spaced legs 6, 6 defining a slot 8 therebetween leading into a throat 10 at the center of the plate. The slot accommodates entry of a

2

king pin 11 on a trailer plate 13, (Figure 2) into the throat for coupling with a coupler mechanism, generally designated 12, as will be readily understood by those skilled in the art.

5 The plate 4 is pivotally supported at each side thereof on a bracket 14 adapted to be mounted on a tractor frame structure indicated at 16, 16.

The coupler mechanism 12 is operable within a housing 18 which is formed integral with the top plate 4, said mechanism comprising a forward member or jaw 20 hingedly or pivotally connected as at 22, 22 to a rear member or jaw 24.

10 The coupler member 20 comprises a central body portion 26 provided with laterally extending wall portions 28 and 30 from which project ledges 32 and 34 slidably supporting the jaw member 20 on flanges 36 and 38, respectively (Figures 2 to 5), of the housing 18.

15 Similarly, the coupler member 24 has a body portion 40 with integral, laterally extending wall portions 42 and 44 provided with ledges 46 and 48 slidably supported on the flanges 36 and 38 of the housing.

20 The body portions 26 and 40 are formed with recesses 50 and 52, respectively, adapted in the closed or coupling position of the coupler members 20 and 24 to define a socket, as shown in Figures 1 to 4, for confining the king pin therein, the recesses being contoured to afford locking engagement between the pin and the coupler members, as will be readily understood by those skilled in the art.

25 In the coupling position of the mechanism as shown in Figures 1 and 2, forward translatory movement of the coupler members 20 and 24 within the housing is restricted by a block of resilient material 54, such as rubber, pocketed in the housing between the front face 56 of member 20 and a front wall 58 of the housing and confined between the top plate 4 and the side walls 30 and bottom wall 60 of the housing.

30 Rearward translatory movement of the members 20 and 24 within the housing in the coupling position of the mechanism is prevented by a locking unit, generally designated 62, and comprising spaced legs or locking portions 64 and 66 in engagement at their forward ends as at 68 and 70, respectively, with complementary faces on the rear sides of wall portions 44 and 42 of the rear coupler member 24. As readily seen in Figure 2, the engaging faces on legs 64 and 66 and portions 44 and 42 are defined from the axis of rotation of unit 62 and are curved vertically.

35 The legs 64 and 66 are integrally formed at their rear ends with depending legs 72 and 74,

respectively, which are integrally united at their lower ends by a crosspiece or bar 76. The locking unit is pivoted on pins 78 and 80 extending through openings formed at the juncture of legs 64, 72 and 66, 74, the pins being suitably secured to brackets 82 and 84 formed on plate 4.

The locking unit 62 is biased or rotated to locking position with the rear coupler member by a plurality of springs 86 and 88, spring 86 being of tension type and having one end hooked around a lug 90 formed on the lower end of the external side of leg 72 of the locking unit. The other end of the spring is hooked to a depending lug 92 on the plate 4 and disposed rearwardly of the locking unit 62.

The other spring 88 is of compression type and at its upper end seats as at 94 against the underside of plate 4 and is positioned thereon by a boss 96 integrally formed on the plate 4. The lower end of the spring 88 extends into a vertical pocket 98 formed in the leg 66 intermediate the ends thereof. The pocket 98 is open through the top of leg 66 and at the bottom thereof is provided with a spring seat 100 affording a seat for the lower end of spring 88. It will be noted that the sides 102 and 104 of the pocket forwardly and rearwardly of the spring 88 diverge upwardly to accommodate rotation of unit 62 without binding or abrading leg 66 against the spring 88, as will be seen from a comparison of Figures 2 to 4.

It will be noted that the action of the springs 86 and 88 in the locked position of the unit 62 prevents the legs 64 and 66 from creeping upwardly out of engagement with the faces on the rear sides of the wall portions 42 and 44 of the rear coupler member 24. Furthermore, failure of either spring or removal of spring 86 by vandals will not affect the operation of the other spring. In addition, the locking means herein described may be readily incorporated in existing coupler assemblies employing the arrangement set forth in the before-mentioned patent to provide a rapid, positive locking action.

The unit 62, including the legs or members 64 and 66, is moved or rotated on the transverse pins 78 and 80 to unlocking or lockset position with the forward ends of said members disposed above out of locking engagement with the rear surfaces of the walls 42 and 44 of the rear jaw 24 by means of a cam member or dog 106 mounted on a shaft 108 supported for rotation on a bearing provided in a bracket 110 (Figure 2) formed on the plate 4.

The cam member is disposed beneath the leg 64 of the locking unit 62 and is provided on its top side, forwardly of its rotational axis 112 (Figure 5), with an arcuate cam surface 114 adapted to engage a cam surface on the underside of a lug 116 disposed on the outer side of leg 64 intermediate the ends thereof.

The cam member is rotated in a counterclockwise direction (Figures 1 and 5) by an operating assembly, generally designated 118, to raise the legs 64 and 66 to unlocking position as shown in Figures 3 to 5 whereupon spring 86 is expanded and spring 88 is compressed. The operating assembly will not be described inasmuch as it forms no part of the present invention and is adequately explained in the before-mentioned patent.

The unit 62 is maintained in locked position with the legs 64 and 66 thereof raised above the wall portions of the rear coupler member 24 by the forward end of the cam engaging behind a shoulder 120 on the underside of lug 116 intermediate the ends thereof.

In the lockset position of the locking means, as seen in Figures 3 and 5, the front and rear coupler members are permitted rearward movement within the housing. Rearward movement

5 of the members 20 and 24 is effected by moving the tractor (not shown), on which the fifth wheel assembly is mounted, in a forward direction. The king pin 11, which is disposed in the socket, causes the members 20 and 24 to slide rearwardly on their ledges along the flanges 36 and 38 of the housing.

It will be noted that the top sides of wall portions 42 and 44 of member 24 are provided with curved surfaces 122 and 124, respectively, adapted 15 to engage the undersides of the legs 66 and 64, respectively, when members 20 and 24 are moved rearwardly whereby the legs are raised to a position disengaging the cam from the shoulder 120 whereupon the cam is caused to rotate in a clockwise direction (Figures 1 and 5) by the operating means 118.

It will be noted that the flanges 36 and 38 of the housing are curved downwardly rearwardly at 126 and 128, respectively, and that the undersurfaces of the flanges 46 and 48 are curved downwardly at 130 and 132 from the forward ends of said ledges to points intermediate the ends of said ledges whereby, as said ledges ride on the curved surfaces 126 and 128 of the housing flanges, the rear member 24 is caused to rotate downwardly at the pivot points 22, 22, thus opening the king pin confining socket and permitting exit of the king pin from the throat 10 of the plate through the slot 3, effecting uncoupling of the tractor and trailer.

It will be seen from a consideration of Figure 4 that in the uncoupling position of the coupler, the legs 64 and 66 abut against the rear sides of the walls 28 and 30 of the front jaw 20, preventing the coupler from falling out of the housing.

To couple, the king pin is entered through the slot 3 into the throat 10 whereupon it engages the forward jaw 20 within recess 50. The front member is moved forwardly into the housing, pulling the rear member which, riding on its faces 130 and 132 against surfaces 126 and 128, is caused to rotate initially and engage the pin within recesses 52. During this action the legs 64 and 66 ride on their undersurfaces along faces 124 and 122, respectively. Thereafter, member 24 rides on flat surfaces 134 and 136 formed on the lugs 46 and 48 thereof adjacent their rear ends. The members 20 and 24 are moved forwardly by the king pin until the block 54 is engaged by the forward face 56 of member 20 and compressed between said face and said front wall 58 of the housing, whereupon the legs 64 and 66 slide off the top surfaces 124 and 122 on the top sides of the wall portions 42 and 44 of member 24 and engage at their front ends the rear faces of said wall portions 42 and 44. It will be noted that the springs 86 and 88 constantly bias the legs 64 and 66 downwardly so that there is no possibility of the coupler members rebounding rearwardly with the king pin before the forward ends of legs 64 and 66 engage behind the walls 42 and 44 of member 24, thus preventing accidental uncoupling between the tractor and the trailer.

It will be noted that in the locked position of unit 62 the rear end of the cam member 106 is engageable as at 140 with an abutment surface 142 at the forward side of leg 72.

75 To uncouple, the cam member is again rotated

to lockset the legs and the procedure repeated as hereinbefore set forth.

Referring now to Figures 7 to 9, it will be noted that the arrangement is similar to that heretofore described and corresponding parts are indicated by corresponding reference numerals. In the present embodiment the tension spring is eliminated and the locking member, generally designated 200, comprises spaced legs 202 and 204 connected at the axis of rotation of the member 200 to depending legs 206 and 208, respectively, said legs 206 and 208 being interconnected by a transverse member or bar 210. Each leg 202 and 204 is provided on the top side thereof with a pocket 212 affording a spring seat as at 214 for the lower end of a compression spring 216. Each pocket 212 is provided with upwardly diverging sides 218 and 220 forwardly and rearwardly of the associated spring 216 to prevent binding. Each spring 216 seats at its upper end as at 222 against the underside of the plate 4 and is positioned by a surrounding, depending boss 224 on the plate 4. The boss 216 comprises downwardly diverging surfaces forwardly and rearwardly of the spring.

The operation of the locking member 200 is the same as in the previous embodiment and is raised to lockset position as shown in Figure 8 by means of the cam 106 which locks behind the shoulder 120. The coupler is opened by moving the coupler rearwardly whereupon the surfaces 122 and 124 on rear jaw 24 are caused to engage the under-surfaces of the legs 204 and 202, causing the locking member 200 to rotate upwardly in a clockwise direction (Figure 7) or counterclockwise direction (Figure 8) to disengage the cam 106 from the shoulder 120 whereupon the cam is permitted to rotate in a clockwise direction (Figure 8). As in the previous embodiment, the rear end 140 of the cam member is engageable with an abutment surface 142 on the leg 206 of the locking member when the locking member 200 is in locked position, as shown in Figure 7, with the coupler 12.

It will be understood that in each embodiment the sides of the spring pockets adjacent to and remote from the axis of rotation of the locking member are arranged in such a manner that in locked position of the locking member the sides adjacent to the axis extend substantially parallel to the axis of the associated spring and in locked position of the locking member the faces of the pockets remote from the axis of rotation of the locking member are substantially parallel to the axis of the spring.

The dual spring arrangement at opposite sides of the locking member tends to equalize wear at the pivot points and tends to balance the locking member against transaxial rotation.

I claim:

1. In a fifth wheel coupling arrangement, the combination of a fifth wheel structure, forward and rear jaws pivoted to each other and slidably supported by said structure for fore and aft movement relative thereto, said structure having guide means for pivoting the rear jaw upwardly to closed position as the jaws slide forwardly and for accommodating pivotal movement of the rear jaw downwardly to open position as the jaws slide rearwardly, a lock comprising a pair of spaced forwardly projecting locking legs spaced approximately equidistantly from the longitudinal vertical center plane of said structure, a pair of legs depending from respective locking legs, said depending legs being interconnected by a crosspiece, said lock having hubs at

1 the juncture of said locking legs with said de-
2 pending legs, pivot means pivotally connecting
3 said hubs to said structure on a substantially
4 horizontal axis whereby the lock pivots upwardly
5 on said axis to unlocked position and pivots
6 downwardly on said axis to locked position
7 whereat said locking legs abut rearwardly facing
8 surfaces of said rear jaw, a tension spring con-
9 nected at one end thereof to the depending leg
10 at one side of said plane, said spring extending
11 rearwardly from said leg and said spring being
12 connected at its other end to said structure, the
13 longitudinal axis of said spring being defined by
14 a vertical plane approximately parallel to said
15 center plane, a compression spring compressed
16 between the structure and an upwardly facing
17 surface of the locking leg at the opposite side of
18 said plane, said compression spring having its
19 compressional axis defined by a vertical plane ap-
20 proximately parallel to said center plane, whereby
21 said springs are disposed at opposite sides of said
22 center plane approximately equidistantly there-
23 from to bias the lock to locked position, and
24 whereby forces of said springs tend to prevent
25 torsion in said pivot means.

2. In a coupling arrangement, a fifth wheel including a top plate having a downwardly facing spring seat and a rearwardly opening slot, a coupler carried by said wheel beneath said plate, locking means for said coupler comprising an element pivoted to the plate for rotation on an axis to locking position and unlocking position with respect to said coupler, a pocket on said element, and means for constantly urging said element to the locking position thereof comprising a coil spring compressed between said element and said plate on a compressional axis substantially perpendicular to the rotational axis of said element, said pocket having a substantially round bottom complementary to and affording a seat for one end of the spring and said pocket having an oval shaped portion with mutually facing sides diverging from said seat to the open end of said pocket, the opposite end of said spring being engaged with the first mentioned seat, said seats converging rearwardly with respect to each other when the lock is in locked position and said seats converging forwardly with respect to each other when the lock is in unlocked position, said sides being formed and arranged to accommodate free compression and decompression of said spring at all times during rotation of the element on said rotational axis, one of said sides of said pocket facing said rotational axis and being substantially parallel to said compressional axis when the element is in unlocking position and the other of said sides of said pocket being substantially parallel to said compressional axis when the element is in locking position, whereby the compressional axis of said spring is substantially straight at all times to substantially avoid bending stresses on the spring.
